UNITED STATES PATENT OFFICE.

GUSTAV SEGSCHNEIDER, OF YONKERS, NEW YORK.

PILE-WIRE FOR WEAVING.

SPECIFICATION forming part of Letters Patent No. 379,545, dated March 13, 1888.

Application filed July 11, 1887. Serial No. 243,957. (No model.)

To all whom it may concern:

Be it known that I, GUSTAV SEGSCHNEIDER, of Yonkers, in the county of Westchester, State of New York, have invented certain new and useful Improvements in Pile-Wires for Weaving, of which the following is a specification.

This invention relates to an improved pile-wire to be used in looms for making cut-pile fabrics—such as velvet, velveteen, plush, Wilton carpets, &c.—in which the blade or cutting-knife, instead of being made integral with the pile-wire, is made detachable, so that a new blade can be readily inserted, the blade easily kept sharp, and the piles cut with greater facility than with the pile-cutters heretofore in use.

The invention consists of a pile-wire provided with a spring-hook at the outer end, said hook having a groove extending from its inner edge and into the shank of the pile-wire, and serving to support a detachable blade, which is retained by the spring action of the spring-hook.

In the accompanying drawings, Figure 1 represents a side elevation of my improved pile-wire and cutter. Fig. 2 is a vertical transverse section on line x x , Fig. 1, drawn on a larger scale; and Fig. 3 is a side view of the blade as detached from the pile-wire.

Similar letters of reference indicate corresponding parts.

Referring to the drawings, A represents my improved pile-wire, which is bent at the outer end in the shape of a hook, B, said hook being provided at the inner edge with a groove, a , of uniform width, that extends also to some distance along the shank of the pile-wire A, as shown in Fig. 1. A detachable blade, C, is inserted into the hook-shaped end B, and is firmly retained in position in the groove a of the same by the spring action exerted by the outer slightly-bent end b of the same on the blade C, whereby the knife is held rigidly and reliably in position. A series of sharpened

blades, C, is kept ready for use and inserted into the hook-shaped ends of the pile-wires, as required, the blades being more easily handled in sharpening than blades which are formed integral with the pile-wires. The detachable blades can also be tempered better, so as to last much longer while cutting, and effecting a neater and cleaner cut on the pile.

The blade C is shown in detail in Fig. 3, and is provided with a sharp slanting edge tapering toward the base of the blade, and a blunt rear part or heel which fits into the spring-hook B of the pile-wire, and is removed therefrom or inserted therein by placing the wire in a vise and handling the blade with a pair of pliers.

Having thus described my invention, I claim as new and desire to secure by Letters Patent—

1. A combined pile-wire and cutter composed of a pile-wire having a spring-hook at the outer end and a detachable blade retained by said hook, substantially as set forth.

2. A combined pile-wire and cutter composed of a pile-wire having a spring-hook at the outer end, the hook and shank of the pile-wire being provided with a groove at its inner edge, and a detachable blade inserted in said groove and retained by the spring-hook, substantially as set forth.

3. A combined pile-wire and cutter composed of a pile-wire having a bent hook at one end, said hook being provided with a groove at the inner edge and an inwardly-bent outer end, and a detachable blade that is fitted in the groove and retained by the spring action of the inwardly-bent end of the hook, substantially as set forth.

In testimony that I claim the foregoing as my invention I have signed my name in presence of two subscribing witnesses.

GUSTAV SEGSCHNEIDER.
